CLAIM

What we claim is the ornamental design of a connector for data transmission optic fiber, as shown and described.

DESCRIPTION

FIG. 1 is a perspective view of the first embodiment of the design;

FIG. 2 is a front view thereof, the rear view being a mirror image;

FIG. 3 is a left side view thereof;

FIG. 4 is a right side view thereof;

FIG. 5 is a top view thereof;

FIG. 6 is a bottom view thereof;

FIG. 7 is a perspective view of the second embodiment of the design;

FIG. 8 is a front view thereof, the rear view being a mirror image;

FIG. 9 is a left side view thereof;

FIG. 10 is a right side view thereof;

FIG. 11 is a top view thereof; and,

FIG. 12 is a bottom view thereof.
